CIRCULAR KNITTING MACHINE

Henry Harold Holmes and John Cyril Herbert Hurd, Leicester, England, assignors to Wildt and Company Limited, Leicester, England, a British company

Application July 17, 1943, Serial No. 495,148
In Great Britain July 27, 1942

10 Claims. (Cl. 66—14)

This invention relates to circular knitting machines, and concerns those of the kind furnished with patterning mechanism comprising, in combination, a grooved or tricked bed or carrier, independently movable instrumentalities in said bed or carrier formed suchwise as to be adapted to provide patterning butts which are contrastingly formed or/and disposed in different positions, and means for action selectively upon the butts whereby the operation of the instrumentalities can be automatically varied in a prearranged manner for effecting variations as regards the pattern or fancy effects produced in knitted fabric, all as now well understood by those acquainted with the knitting art.

Broadly, the invention is applicable both to plain circular, i. e. non-rib, machines having but a single needle cylinder and to circular rib knitting machines of the kind concerned. In this latter respect the invention may, for instance, be applied to circular rib knitting machines of the type comprising double cylinders arranged coaxially and each adapted to contain needles, or needles and associated jacks or sliders. As examples of such machines may be mentioned those of the characteristic type employing superposed needle cylinders and equipped with double-ended needles operable by sliders whereby needles can be transferred from one cylinder to the other for the purpose of changing from plain knitting to rib knitting and vice versa, and it is principally to such machines that the present invention is intended for application without, however, being limited in this particular respect.

Furthermore, it is primarily the intention to apply the invention to circular knitting machines of the characteristic type referred to equipped with at least two sets of respectively different patterning instruments prearranged in the same grooved or tricked dial mounted within the needle cylinders concentrically therewith, said instruments, or jacks associated therewith, being provided with patterning butts suchwise that when assembled they present banks or groups of such butts respectively in different planes for action upon by selecting means.

Thus, for example, we are aware of a previously proposed machine of this type equipped with a plurality of pelerine instruments interspersed with lap or wrap thread guides in a horizontally disposed inner dial, said instruments and guides being provided with operating butts for engagement with suitable operating cams and having in association therewith selector jacks with patterning butts thereon suchwise that when as-

sembled the jacks present banks or groups of such butts respectively in different planes for action upon by respective selecting cams. Now in this particular prior arrangement the forward end of each selector jack acts against a shoulder on the corresponding instrument or guide, and at its rear end the said jack is formed with a right-angular extension upon which the patterning butts are formed. These butts are provided at respectively different levels so as to be located in correspondingly different planes heightwise. At the or each feed of the machine there is a cam for selecting pelerine instruments and another cam serving to select the lap or wrap thread guides, each of these selecting cams being movable vertically into different planes. For convenience in operation, the patterning butts are divided into upper and lower groups, the butts of one of these two groups serving the pelerine instruments and the butts of the other group serving the thread guides. The movements of the selecting cams at the or each feed are restricted, each cam being movable only to such an extent as to enable it to be moved into any one of the planes of the butts in the corresponding group. This arrangement, however, has certain disadvantages. For instance, to accommodate the right-angular extensions of the selector jacks it is necessary to make vertical cuts in the inner wall of the dial, these cuts extending downwardly and at right angles with respect to the radially extending horizontal tricks or grooves formed in the upper face of the dial for reception of the pelerine instruments and lap or wrap thread guides. That is to say, in addition to being cut with tricks or grooves in the customary manner, the dial has also to be cut internally, and this internal cutting is a difficult process, especially having regard to the fact that the spacing of the tricks or grooves is closest at the inner wall. Moreover, by reason of the inner vertical edges of the aforesaid right-angular extensions coming into contact with the bottoms of the vertical cuts, the selector jacks cannot readily be withdrawn by being pulled straight out of the dial. Added to these difficulties, the tail butts provided on the right-angular extensions take up more space than is desirable.

The primary object of the present invention, therefore, is to provide a circular knitting machine furnished with an improved patterning arrangement designed to overcome the foregoing difficulties in the particular mechanism just described.

55 Bearing in mind its broader aspects, however,

the invention also has for an aim the provision of such a machine equipped with patterning mechanism of such generally improved construction as to increase the capabilities of the machine for patterning or designing, without any material increase in the space occupied by the said mechanism, as will be hereinafter set forth.

According to this invention there is provided a circular knitting machine of the kind herein referred to, wherein the instrumentalities in the grooved or tricked bed or carrier are formed suchwise as to be adapted to provide two separate sets or groups of butts, and there are means for action upon one of said sets or groups to effect a general selection of the instrumentalities and additional means for action upon the other set or group to effect a further selection or separation of the selected instrumentalities.

Instead, therefore, of having a single set or group of patterning butts at one location around the machine capable of producing the particular number of selections required, the idea now is to provide an arrangement in which the butts are in effect divided into two smaller sets or groups provided at respectively different locations and capable of effecting between them at least as great a number of selections as with a single and larger set or group of butts. One of the sets or groups of butts in the improved arrangement is consequently employed to effect what may be regarded as a primary selection of the instrumentalities, while the other or auxiliary set or group is used to effect a secondary selection or a separation by partially neutralising or otherwise modifying the said primary selection. In this way it is possible to achieve economy in space by a more convenient disposition of the patterning butts and the associated means for action thereupon. Moreover, by varying the selections made at successive feeds of a multi-feeder machine, the capabilities of the machine for patterning or designing would be considerable.

The instrumentalities to be selected may be all of the same kind. Preferably, however, instrumentalities of one kind are arranged in the same grooved or tricked bed or carrier together with instrumentalities of another kind or other kinds, in which instance one set of butts common to all of the instruments, or to jacks associated therewith, may conveniently be utilised for a general selection of the said instruments, whilst other butts on the latter may be adapted for co-operation with appropriate means to effect a separation of the selected instruments of one kind from the selected instruments of the other kind, or kinds, as the case may be.

In order that the invention may be more clearly understood and readily carried into practical effect, a specific example thereof, being an improvement in the previously proposed patterning mechanism aforesaid designed to achieve the primary object hereinbefore specified, will now be described with reference to the accompanying drawings, wherein,

Figure 1 is a vertical sectional view of so much of a circular links and links knitting machine as is necessary to illustrate the application of the improved patterning mechanism thereto,

Figure 2 is a plan view showing cams in a portion of the dial cam systems, with the dial cam plate removed, and a few of the instruments of both kinds adapted to be actuated by the said cams, and

Figure 3 is a detail perspective view of the

same as viewed in the direction of the arrow A in Figure 2 and with a cam ring removed to reveal a fragmentary portion of the dial.

Like parts are designated by similar reference characters throughout the drawings.

Referring to Figure 1 it will be seen that the machine comprises a rotary bottom or plain cylinder 1 and a superimposed rotary top or rib cylinder 2, and is equipped with double-ended latch needles such as 3 which are operable by means of bottom and top sliders 4 and 5 respectively whereby needles can be transferred from one cylinder to the other, as occasion demands.

15 In the example depicted there is a plurality of pelerine instruments 6 arranged together with lap or wrap thread guides 7 in radial tricks or grooves 8a formed in the upper face of a horizontally disposed rotary dial 8 which is mounted within 20 and concentrically with the rotary needle cylinders 1 and 2. The pelerine instruments may be interspersed with lap or wrap thread guides in the dial 8, or the said instruments and guides may be prearranged in definite groups or panels, 25 according to requirements. Each of the pelerine instruments is of blade-like form and at its operative end is laterally offset so as to have an arched formation 6a the opposite ends of which are in alignment with the remainder of the 30 blade. The tip 6b of the instrument is in the form of a nib and it also has a loop engaging shoulder 6c at a suitable distance from the tip. If desired, and as shown in Figure 2, the pelerine instruments may be used in pairs, i. e. left hand 35 and right hand. Each of the lap or wrap thread guides 7 is also a blade-like form and is recessed at its lower edge as at 7a in the region of its operative end suchwise as to provide a downwardly directed right-angular extension 7b which 40 is bent laterally and thereby obliquely disposed with respect to the main portion of the guide (see Figure 2). The extension has holes 7c appropriately disposed therein for the passage of a design thread.

45 At their rear, i. e. inner, ends both the pelerine instruments 6 and the lap or wrap thread guides 7 have patterning butts 9 thereon arranged so as to present a single bank or group of tail butts for action upon by selecting cams. These butts 50 are provided at different levels so as to be located in correspondingly different planes heightwise. If desired, each pelerine instrument and each lap or wrap thread guide may initially be formed with a full complement of frangible butts 55 9 like that shown in Figure 1 and which butts can be readily broken off according to requirements. The important point to note here is that since the single bank or group of tail butts 9 is to serve for selection of both the pelerine instruments and the lap or wrap thread guides, the total height of the full complement of butts need not exceed, or at any rate substantially exceed, the width of the blades of the said instruments and guides; thus, referring to Figure 1, the 60 height h of the full complement of six tail butts 9 only slightly exceeds the width w of the instruments 6 and guides 7. This enables the butts to be so disposed that they will not prevent the instruments and guides from being completely 65 withdrawn longitudinally from their tricks or grooves 8a. At each feed of the machine (assuming it to be a multi-feeder machine) there are provided two selecting cams 10 and 11 spaced apart somewhat circumferentially. Each of 70 these selecting cams is horizontally disposed and 75

movable vertically under suitable control into any one of the different planes occupied by the tail butts. Conveniently the said cams may be pattern controlled through any suitable intermediate connections, such as those indicated at 12 and 13 in Figure 1, from a pattern device or unit, not shown. Thus, as will be understood, each selecting cam is common to the pelerine instruments 6 and the lap or wrap thread guides 7. Consequently, whenever one of the selecting cams at the feed is rendered operative by being moved into one of the aforesaid planes, all of the instruments and guides having a tail butt 9 at the corresponding height will be selected and advanced, i. e. pushed radially outwards, by the said cam. The importance of this is that by providing tail butts in, say, six different planes heightwise it is possible to achieve six different selections of the pelerine instruments 6 and also six selections of the lap or wrap thread guides 7, in contradistinction to the particular prior arrangement hereinbefore described wherein tail butts in twelve different planes would be necessary to achieve a similar result.

The upper edge of each pelerine instrument and lap or wrap thread guide is so formed as to provide thereon an upstanding butt, the butts 14 on the said instruments being short, and those, 15, on the thread guides long. If desired, the instruments 6 and guides 7 may be so arranged in the dial 8 that the short and long upstanding butts alternate, although, of course, this is by no means essential.

A dial cam plate 16 is fixedly supported immediately above the dial 8 and on its underside is furnished with cams, hereinafter to be described with reference to Figure 2, for action upon the upstanding butts 14 and 15. Both the short and the long upstanding butts are all normally located in a common track 17 from which they are diverted selectively by the selecting cams for admission to dial cam systems whereby the requisite advancing and retracting movements are imparted to selected instruments and guides and to which track the said butts are always returned for re-selection.

Consider first the operation of the lap or wrap thread guides 7 at one of the feeds, assuming that all of the upstanding butts are initially in the common track 17 and that the needle cylinders and the dial 8 are rotating together in the direction of the arrow B in each of Figures 2 and 3. If, now, the two selecting cams at the feed are pre-selected and rendered operative, the cam 10 will first act upon all of the tail butts 9 in the appropriate plane thereby effecting a primary selection both of pelerine instruments and lap or wrap thread guides. As a result, the instruments and guides so selected will be actuated and moved radially outwards to an extent sufficient to bring their upstanding butts into the range of a combined advancing and retracting cam 18 formed with an appropriately inclined advancing edge 18a. The underside of the forward portion of this cam is, however, cut away and reduced in thickness at 18b with the result that only the long butts 15 will be landed onto the advancing edge 18a, the short butts 14 being missed so that they merely pass idly beneath the cut away portion. This will be more clearly appreciated from a consideration of Figures 2 and 3 in each of which one of the long butts which has been landed onto the edge 18a is designated by the numeral 15¹, while a short butt passing idly beneath the cut away portion is

indicated at 14¹. As a consequence, the selected lap or wrap thread guides 7 will be fully projected by the cam 18 to carry their embroidery threads across the needle circle NC from the inside to the outside thereof in well known manner, while any further advance of the pelerine instruments 6 will be effectively prevented. A fully advanced lap or wrap thread guide is indicated at 7¹ in Figure 2. Adjacent to the aforesaid cut away portion, the cam 18 is formed with an oppositely inclined retracting edge 18c adapted for action only upon the short butts 14 to restore the pelerine instruments 6 to the common track 17 at this point. As will be appreciated, therefore, the primary selection of the pelerine instruments is neutralised by the thickest portion of the combined advancing and retracting cam 18, leaving only the selected lap or wrap thread guides to be operated in known manner. After being fully projected in the manner described, the selected lap or wrap thread guides are fully retracted by contact of the appropriate long butts 15 with an adjacent cam 19 which latter functions to restore said butts to the common track 17 for re-selection.

Selected pelerine instruments are thereafter operated at the same feed. To this end all of the tail butts 9 in a desired plane are next acted upon by the second selecting cam 11 so that the corresponding instruments and guides will be selected and partially advanced. By reason of this selection, the short and long upstanding butts 14 and 15 respectively on the selected instruments and guides are brought into the range of superposed cam portions 19 and 20 whereby the said long butts 15 are restored to the common track 17 to render selected thread guides inoperative, and the short butts 14 are partially advanced so as to push forward the corresponding pelerine instruments to an extent just sufficient to enable yarn to be collected, i. e. laid over, their nibs 6b to form sinker loops. In Figure 2 the pair of pelerine instruments having short butts marked 14¹ are partially advanced, these instruments being subsequently fully advanced by a cam 21 to effect expansion of the formed sinker loop laterally in both directions for transfer to appropriate needles 3 in the bottom needle cylinder 1. The upper one, 19, of the two superposed cam portions is formed with an appropriately inclined retracting edge 19a and is supported by the lower cam portion 20 at such a height as to miss the short butts 14, whereas the said lower cam portion is formed with an oppositely inclined advancing edge 20a. The lower cam portion 20 may, as shown in Figure 3, be rebated or recessed to receive the upper cam portion 19, the two portions being rigidly secured together. Alternatively, these two cam portions may be made in one piece. In the result, therefore, the machine just described is such that at each feed a primary or general selection of the pelerine instruments and lap or wrap thread guides can be effected at each of two circumferentially spaced points, the selection of the pelerine instruments being neutralised at one of said points to leave only selected thread guides operative, and the selection of the thread guides being similarly neutralised at the other point to leave only selected pelerine instruments operative.

The specific form of the improved patterning mechanism herein described by way of example is applicable to the production of any patterned knitted fabric comprising, in combination, peler-

ine stitch effects and lap or wrap or embroidery thread effects. The mechanism may be arranged to produce the pelerine loops or stitches and the lap or wrap or embroidery stitches either in direct association or separately in different wales of the knitted fabric.

Compared with the prior arrangement concerned the particular constructional form of the invention herein described has tail butts in only half the number of planes, and yet the capabilities of the machine for patterning are not in anywise reduced.

What we claim then is:

1. In a circular knitting machine, in combination, a grooved bed, independently movable pelerine instruments prearranged in said bed, lap thread guides also prearranged in the bed together with the pelerine instruments, said instruments and guides having patterning butts which are divided into separate primary and secondary groups, means for action selectively upon the primary butts to effect a general selection amongst all of the pelerine instruments and lap thread guides, and means for thereafter co-operating with the secondary butts suchwise that selected pelerine instruments are restored to their original inoperative positions, thereby leaving the selected lap thread guides to be operated as required.

2. In a circular knitting machine, in combination, a grooved bed, independently movable pelerine instruments prearranged in said bed, lap thread guides also prearranged in the bed together with the pelerine instruments, said instruments and guides having patterning butts which are divided into separate primary and secondary groups, means for action selectively upon the primary butts to effect a general selection amongst all of the pelerine instruments and lap thread guides, and means for thereafter co-operating with the secondary butts suchwise that selected lap thread guides are restored to their original inoperative positions, thereby leaving the selected pelerine instruments to be operated as required.

3. In a circular knitting machine, in combination, a grooved bed, independently movable transfer instruments prearranged in said bed, lap thread guides also prearranged in the bed together with the transfer instruments, means at each of two circumferentially spaced points for effecting a primary selection amongst all of the said instruments and guides, means for neutralising the selection of the transfer instruments at one of said points to leave only selected thread guides operative, and means for similarly neutralising the selection of the thread guides at the other point to leave only selected transfer instruments operative.

4. In a circular knitting machine, in combination, a grooved bed, two respectively different kinds of independently movable instruments interspersed in said bed, said instruments having associated therewith primary selecting butts so arranged as to provide series of such butts respectively in different planes but with the butts of one kind of instruments in the same series of planes as the butts of the other kind of said instruments, and secondary butts which are adapted for operating the two kinds of instruments, means for action selectively upon the said primary butts to effect a general selection amongst all of the instruments of both kinds, and means for thereafter co-operating with the secondary butts so that selected instruments of one kind are

restored to their original inoperative positions thereby leaving the selected instruments of the other kind to be operated as required.

5. In a circular knitting machine, in combination, a grooved bed, two respectively different kinds of independently movable instruments interspersed in said bed, said instruments having associated therewith primary selecting butts so arranged as to provide series of such butts respectively in different planes but with the butts of one kind of instruments in the same series of planes as the butts of the other kind of said instruments, and secondary butts which are adapted for operating the two kinds of instruments, at least one selecting cam which is movable into any one of the different planes for action selectively upon primary butts to effect an initial selection of the instruments, and means for action upon the secondary butts to effect a subsequent separation of the selected instruments of one kind from the selected instruments of another kind.

10 15 20 25 30 35 40 45 50 55 60 65 70 75

6. In a circular knitting machine, in combination, a grooved bed, two respectively different kinds of independently movable instruments interspersed in said bed, said instruments being formed with primary selecting butts so arranged as to provide series of such butts respectively in different planes but with the butts of one kind of instruments in the same series of planes as

the butts of the other kind of said instruments and long and short secondary butts adapted for operating the two kinds of instruments, means for action selectively upon the primary butts to effect a general selection amongst all of the instruments of both kinds, and cam means for thereafter so co-operating with the secondary butts that selected long butt instruments are advanced while initially selected short butt instruments are restored to their original inoperative positions.

7. In a circular knitting machine, in combination, a grooved bed, two respectively different kinds of independently movable instruments interspersed in said bed, said instruments being formed with primary selecting butts so arranged as to provide series of such butts respectively in different planes but with the butts of one kind of instruments in the same series of planes as the butts of the other kind of said instruments and long and short secondary butts adapted for operating the two kinds of instruments, selecting cams for action selectively upon the primary butts to effect a general selection amongst all of the instruments of both kinds, and cam means for thereafter so co-operating with the secondary butts that selected long butt instruments are advanced while initially selected short butt instruments are restored to their original inoperative positions.

40 45 50 55 60 65 70 75

8. In a circular knitting machine, in combination, a grooved bed, two respectively different kinds of independently movable instruments interspersed in said bed, said instruments being formed with primary selecting butts so arranged as to provide series of such butts respectively in different planes but with the butts of one kind of instruments in the same series of planes as the butts of the other kind of said instruments and long and short secondary butts adapted for operating the two kinds of instruments, selecting cams for the purpose herein described.

9. In a circular knitting machine, in combination, a grooved bed, two respectively different kinds of independently movable instruments interspersed in said bed, said instruments being formed with primary selecting butts so arranged as to provide series of such butts respectively in different planes but with the butts of one kind of instruments in the same series of planes as the butts of the other kind of said instruments and long and short secondary butts adapted for operating the two kinds of instruments, selecting

cams for action selectively upon the primary butts to effect a general selection amongst all of the instruments of both kinds, cams providing between them a common track in which both the long and the short secondary butts are normally located and to which track said secondary butts are always returned for re-selection, and a cam system whereby the requisite advancing and retracting movements are imparted to selected instruments and to which the corresponding secondary butts are admitted upon diversion from the common track by co-operation thereof with the selecting cams, said system including a combined advancing and retracting cam a portion of which latter is reduced in thickness so that only long butts will be landed onto the advancing edge of the cam, the short butts being missed and engaged by an oppositely inclined retracting edge on the said cam, for the purpose herein specified.

9. In a circular knitting machine, in combination, a grooved bed, two respectively different kinds of independently movable instruments interspersed in said bed, said instruments being formed with primary selecting butts so arranged as to provide series of such butts respectively in different planes but with the butts of one kind of instruments in the same series of planes as the butts of the other kind of said instruments and long and short secondary butts adapted for operating the two kinds of instruments, two selecting cams for action selectively upon the primary butts to effect a general selection amongst all of the instruments of both kinds, cams providing between them a common track in which both the long and the short secondary butts are normally located and to which track said secondary butts are always returned for re-selection, a combined advancing and retracting cam into the range of which predetermined secondary butts are moved upon diversion from the common track by co-

operation thereof with one of the selecting cams, a portion of said combined cam being reduced in thickness so that only long butts will be landed onto the advancing edge of the cam while the short butts are missed and engaged by an oppositely inclined retracting edge on the said cam, and further cams into the range of which secondary butts are subsequently moved by engagement with the other of the two selecting cams, said last mentioned cams being adapted to restore long butts to the common track while at the same time advancing the short butts, for the purpose herein specified.

10. In a circular knitting machine, in combination, a radially grooved dial, two respectively different kinds of independently movable blade-like instruments mounted in the grooves in said dial, said instruments being formed with (a) primary butts so arranged at the tail ends of the instruments as to provide a series of such butts respectively in different planes but with the butts of one kind of instruments in the same series of planes as the butts of the other kind of said instruments so that there is a single bank of primary butts the total height of which does not substantially exceed the width of the blades of the said instruments suchwise as to facilitate complete withdrawal of the latter from the grooves as occasion demands, and (b) secondary butts which are adapted for operating the two kinds of instruments, at least one selecting cam which is movable into any one of the aforesaid planes for action selectively upon primary butts to effect an initial selection of the instruments, and means for action upon the secondary butts to effect a subsequent separation of the selected instruments of one kind from the selected instruments of another kind.

HENRY HAROLD HOLMES.

JOHN CYRIL HERBERT HURD.
